EDWARD A. MELLINGER, OF CHICAGO, ILLINOIS, ASSIGNOR, BY MESNE ASSIGNMENTS,
TO FIRST TRUST AND SAVINGS BANK, TRUSTEE, OF CHICAGO, ILLINOIS.

PARTY-LINE AUTOMATIC TELEPHONE SYSTEM.

1,176,716.

Specification of Letters Patent.

Patented Mar. 21, 1916.

Application filed July 9, 1907. Serial No. 382,914.

To all whom it may concern:

Be it known that I, EDWARD A. MELLINGER, a citizen of the United States of America, and resident of Chicago, Cook county, Illinois, have invented a certain new and useful Improvement in Party-Line Automatic Telephone Systems, of which the following is a specification.

My invention relates to telephone systems 10 in general, but more particularly to automatic telephone exchange systems, and especially to systems in which a plurality of subscribers' stations are located on the same line—that is to say, systems in which party-lines are employed.

In certain respects my present invention is 20 in the nature of an improvement on party-line systems in which a relay is provided for momentarily removing the guarding potential from the calling line, to permit a subscriber thereon to call another subscriber on the same line. This relay controls a circuit through the bridge-cut-off relay of the calling line. For this reason prior to my present 25 invention it was found that in releasing, the said cut-off relay was liable to be de-energized, with the result that the trip magnet of the individual switch of the line would be energized. This was found to result 30 in leaving the individual switch off-normal, which, of course, would occasion some trouble.

The principal object of my present invention is, therefore, to provide an improved 35 system of the foregoing character in which the switches can be released without any liability of energizing the trip magnet of the party-line, and whereby there will be no danger of the individual trunking switch 40 being left off normal after the subscribers are through talking.

It is also an object, of course, to provide certain details and features of improvement and combinations tending to increase the 45 general efficiency of a telephone exchange system of this particular character.

To the foregoing and other useful ends, my invention consists in matters hereinafter set forth and claimed.

50 In the accompanying drawings Figure 1 is a diagrammatic representation of a party-line system embodying the principles of my invention. One of the substations, #420, is represented as having called the substation #220 through the line switch C, first-selector D and connector E, back to the same line

which is allotted to the three substations #220, #320, and #420. Fig. 2 represents, also diagrammatically, but more fully, the line switch C and the controlling master switch H. Fig. 3 is a detail view of the master switch bank O. Figs. 4, 5, 6, 7, 8, 9 and 10 are detail views of the substation impulse springs, showing the said springs in various positions.

The substations may be of any suitable or approved type. Those in connection with which I have elected to illustrate my invention are alike. Substation A, for example, comprises a receiver 2, a switch-hook 3 for controlling the substation circuits, which controlling operations are accomplished through the medium of any suitable means, such as the cam-arms 4, 5 and 6. As the switch-hook is lowered the cam-arm 4 momentarily presses the release springs 7, 8 and 9 into engagement, whereby the substation line conductors may be grounded simultaneously. When the switch-hook is down the cam-arm 5 engages the spring 10, thereby bridging the ringer 11 in series with the condenser 12 across the line. Furthermore, when the switch-hook is down the said cam-arm 5 disengages the springs 13, 14 and 15, thus breaking the local battery circuit which includes in series the primary winding 15^a, transmitter 16 and local battery 17. When the springs 13 and 14 disengage, the lock-out relay 17^a is disconnected from the vertical line conductor. The substation ground circuit is normally broken between the ground springs 18 and 19 by the cam-arm 6; but when said springs are together, and the relay 17^a is in normal condition, ground is provided to the ground post 20 and to the release spring 7, as is usually the case in telephones of this type. The said substation comprises the usual induction-coil 21 having the primary winding 15^a and secondary winding 22. Being an automatic 100 substation, it is provided with the usual vertical and rotary impulse springs 23 and 24. Said substation is, of course, provided with a dial (not shown) which is secured to the shaft 25, together with the locking dog 26. Furthermore, there is a locking cam 27 that locks the dog 26 while the receiver is on the switch-hook, to prevent a rotation of the dial. For operating the impulse springs 23 and 24 the substation is provided with an 110 impulse wheel 28 that is secured to the shaft, which impulse wheel carries on its pe-

riphery the so-called vertical impulse teeth 29 and one rotary impulse tooth 30. The said impulse teeth are so arranged that when the dial is drawn down the impulse 5 spring 23 is not carried into contact with the ground post 20; but as the dial returns, first the vertical teeth engage the vertical impulse spring 23, and after they have completed their work the rotary impulse tooth 10 30 operates the rotary impulse spring 24. In this operation the subscriber's vertical line conductor 31 is first given a number of ground impulses, and then the rotary line conductor 32 is given one ground impulse. 15 The vertical impulse spring 23 is provided with an oblique projection or lug 250 (Fig. 4) on the under side, with which the vertical impulse teeth 29 are adapted to engage for driving the spring 23 intermittently onto 20 the ground post 20. The rotary impulse spring 24 is provided with somewhat similar mechanism for driving the said rotary spring onto the ground post, once when the dial is rotated in one direction, and once 25 when rotated in the opposite direction. The said rotary impulse spring 24 has on its under side a V-shaped member 251 having two sides *c* and *d*. In addition, there is an auxiliary spring 252 which works in conjunction 30 with the said V-shaped member. As shown more clearly in Fig. 4, the auxiliary spring 252 is provided with a lower curved part 253 having the rear section 254 curving outwardly, as shown also in Figs. 5, 6, 7, 8, 35 9 and 10. The front section 255 of said member 253 is designed to fall just below the apex of the V-shaped member 251, so that the rotary impulse tooth 30, when moving in the direction indicated by the arrow 40 in Fig. 5, will pass onto the curved member 253, thus pressing the rotary impulse spring 24 onto the ground post 20 for a comparatively long time, as shown in Fig. 6, thus sending to the rotary line a comparatively 45 long impulse. As the impulse wheel advances, the vertical impulse teeth 29 approach the lug 250 of the vertical impulse spring 23 (Fig. 6), and eventually the first tooth *f* that meets the lug 250 clears the said 50 lug, as shown in Fig. 7, but not until after the rotary impulse tooth 30 clears the curved member 253. As the impulse wheel continues to advance in the direction indicated by the arrow in Fig. 7, the succeeding impulse tooth will clear the projection 250, as 55 shown in Fig. 8. Then when the impulse wheel is released, first the vertical impulse spring 23 is carried into engagement with the ground post 20 twice by the vertical impulse teeth previously cleared, as indicated 60 in Fig. 9; but as the impulse wheel nears its normal position the rotary impulse tooth 30 passes under the curved member 253 of the auxiliary spring 252 (Fig. 10), engaging the 65 V-shaped member 251 for a short time only, sending the ordinary impulse to the rotary line through the medium of the rotary impulse spring 24; after which the said member 251 is cleared, as shown in Fig. 5, as the impulse wheel reaches its normal position. 70 The operations, as thus described, are repeated each time that the dial is operated, and the number of impulses produced through the medium of the vertical impulse spring 23 are accurately and definitely determined at each operation of the dial by the finger-hole which the subscriber previously selects on the dial. The means whereby the subscriber may signal the called subscriber comprises the push-button spring 35 which 75 normally engages the contact point 36; but when the button 37 is pressed the spring 35 engages the contact point 38, whereby the vertical line conductor 31 may be grounded. The substation is also provided with a 80 governor (not shown) for controlling the speed of the impulse wheel 28 and the switch-hook 3. Furthermore, the lock-out relay 17^a is provided with the armature 39, so that when the relay is energized as the 85 switch-hook 3 is moving up, the armature 39 is attracted, disengaging the springs 40 and 41, and the armature is locked in its attracted position by the locking spring 42, as shown at substation #220; but when the 90 switch-hook is lowered the rod 43, which is attached to the switch-hook 3, slides downward in front of the armature 39, carrying the locking spring 42 out of engagement with the armature 39. The individual 95 or line switch C (Fig. 2) is of the general form disclosed in British Patent No. 26301 of 1906. The said switch comprises a plunger 44, plunger-arm 45, bridge-cut-off relay 46, trip magnet 47 and switch-release magnet 48, all of which are built about a switch-base or frame (not shown). The said switch-release magnet is provided with an armature 49 that is pivoted on a pin 50 which rises from the base of the switch. 100 The said armature carries pivotally secured on its end a second armature 51 that is controlled by the trip magnet 47. The pin 52 about which the armature 51 oscillates is carried on the end of the armature 49. The 105 plunger 44 is pivotally secured by the pin 53 to the plunger-arm 45, which latter is in turn pivoted to a pin 54 that rises from the switch frame. The lug 55 is stamped out of the side of the frame and is provided as 110 a stop or rest for the armature 49. Upon the armature 51 is secured the catch spring 56 which is adapted to engage the end 57 of the plunger-arm 45. Furthermore, the said 115 line switch is provided with a bank of terminals, usually ten in number but only one of which is shown at Q in Fig. 2. As shown, the said terminal Q is turned from its true 120 position with respect to the swing of the plunger 44, and the bushing 62 is corre- 125 130

spondingly turned, all for the purpose of making the illustration clearer. The terminal Q comprises the springs 63 and 64, 65 and 66, 67 and 68, and 69 and 70. The said 5 springs are normally disconnected from each other, but are driven into contact in the above-mentioned order when the plunger 44 operates. When the plunger 44 is in locked engagement with the plunger shaft 60, the notch 61 is in engagement with the flange or web of the shaft 60, and when in sliding engagement the end 59 rests in the position shown by the dotted lines in Fig. 2—that is, when the plunger shaft is operated the plunger 10 44 is not carried along with the locked plungers, but remains in the dotted position, the plunger shaft sliding upon the end 59. Normally, however, the plunger 44 is retained out of engagement with the line 15 switch bank, and in engagement with the plunger-controlling shaft 60, which latter is operated by the master switch H. The general operation of the switch is as follows: The trip magnet 47 is energized by a preliminary impulse, and the armature 51 is attracted against the magnet cores. When the armature 51 is attached the catch 56 slides out of contact with the end 57 of the plunger-arm 45, and the said plunger-arm 20 45, owing to the tension of the spring 58, moves about the pin 54 and thrusts the plunger 44 into the bank terminal Q, shown in Fig. 2; and when the trip magnet again de-energizes, the trip armature 51 falls against the end of the plunger-arm 45. The switch 25 is restored when the release magnet 48 becomes energized, whereby the armature 49 is attracted, and accordingly the trip armature 51 is moved upwardly until the catch 56 slides over the end 57; then when the release magnet 48 becomes deenergized the armature 49 returns to normal position and remains at rest against the stop 55. Furthermore, since the plunger-arm 45 is 30 45 now in engagement with the armature 51, the said plunger-arm is also moved about the pin 54, whereby the plunger 44 is moved from the terminal Q. Also, since the plunger shaft has advanced one step, the hub 59 50 of the plunger 44 comes to rest in the position shown by the dotted lines in Fig. 2, against the plunger shaft 60, and as the said plunger shaft advances each time an idle trunk is seized, the plunger 44 is not advanced, but remains in this position and opposite the trunk terminal from which it has just disengaged, since the slot 61 is not in engagement with the plunger shaft 60. After all the trunk lines have been 55 55 successively seized, and the shaft 60 is released from its last position, said shaft then starts toward home or starting point and picks up the plunger 44, when the flange or web of the said shaft, over which the slot 61 normally rides, arrives at the position from

which the plunger 44 was originally released. From thence on the plunger 44 is carried by the shaft 60 until it is again released when another call is made. But if after the plunger is released, and before the shaft 60 returns to pick up said plunger, the switch C is again operated, the plunger 44 again engages the same terminal Q.

The master switch H, which may be of any suitable or approved type, is provided for operating the plunger shaft 60, and for controlling certain circuits that will be disclosed hereinafter. It comprises the following details: a motor magnet 71 for operating the ratchet wheel 72, which latter is 75 designed for operating the plunger shaft 60 through the medium of the cam-arm 76, and a differential relay 73 for controlling the energizing circuit of the motor magnet 71. The said master switch also has a bank O 80 comprising a plurality of individual contact segments *a* and a common metallic segment 74, as shown in Figs. 2 and 3. The individual segments *a* are separated from the common segment 74 (Fig. 3) by the insulating strip 72^a. The insulating member 73^a is provided so that when the wiper 75 passes from the extreme left contact 84 to the extreme right contact 84, the upper part 75^a slides on the piece 73^b, thus preventing 85 the wiper arm 75 from placing the contact segments *a* in connection with the common segment 74, whereby some interference might be experienced by the master switch. The wiper 75 is adapted to remain in constant engagement with the bank O, and to maintain at all times some one of the segments *a* in electrical connection with the common segment 74, except when the wiper 75 passes from the extreme left contact 84 to the extreme right contact 84, as explained. The wiper 75 is operated in a step-by-step manner by the ratchet wheel 72, through the medium of a cam member 76 rigidly secured to the said wiper 75 and adapted to successively engage the pins 77, 78, 79 and 80 upon the said ratchet wheel 72. The motor magnet 71 is provided with an armature 81 upon the end of which there is suitably secured a pawl 82. Each time that the said magnet is energized the pawl 82 engages the ratchet wheel 72, advancing the latter one step. It will be seen, therefore, that as the ratchet wheel 72 advances, the wiper 75 also advances step-by-step from right to left, and when the pin 77, for instance, clears the cam 73 the retracting spring 83 restores the wiper 75 to its first position at the right of the bank O and in engagement with the first segment 84. The said motor magnet 71 is 90 provided with a couple of interrupter springs 85 and 86 that are included in the energizing circuit of the said motor magnet, which energizing circuit also comprises the springs 87 and 88 controlled by the dif- 95 100 105 110 115 120 125 130

ferential relay 73. Therefore, whenever the differential relay 73 is energized the springs 87 and 88 are pressed into contact, and the motor magnet 71 operates step-by-step as long as the differential relay 73 remains energized. Further, it is assumed that the terminal Q of the line switch C is the first terminal of the line switch bank. The plunger 44, while in normal locking engagement with the shaft 60, is retained in front of said terminal by the plunger shaft 60, whenever the master switch wiper 75 is in engagement with the bank segment 84; but as the motor magnet 71 advances the wiper 75 onto the second segment 89, the said plunger and all idle plungers similarly engaging the shaft 60 are carried opposite the next terminal of the line switch bank.

It should be noted that in each switch bank all of the springs 63 are permanently connected and may be made of one common piece; the springs 64, however, are individual—that is, there is one separate and distinct spring for every terminal Q, there being ten in the bank. The springs 65, 67 and 69, like the springs 63, are also common, and the springs 66, 68 and 70, like the springs 64, are individual. For every bank terminal Q there is a trunk line of three conductors 90, 91 and 92 leading to a selector; and there is also a normal trunk line comprising the conductors 93, 94 and 95 leading to the connector banks. The subscriber's line conductors 31 and 32 terminate in the springs 63 and 65 which, as has been stated, are common springs. When the subscriber operates the line switch C, and the plunger 44 engages the terminal Q, the subscriber's line conductors 31 and 32 are extended to the vertical and rotary conductors 90 and 91, thence to the switch D.

As shown in Fig. 1, the private normal relays 113 and 114 are bridged across the trunk line conductors 90 and 91. The arrangement of these relays is such that when impulses are passing over the vertical line conductor the vertical private normal relay 113 energizes and operates to place the spring 123 in contact with the ground spring 124; and the rotary private normal relay 114 operates to disengage the springs 116 and 117 when the rotary impulses pass over the rotary line conductor. This arrangement is provided in order that a subscriber may call back upon his own line—that is, when a rotary impulse is delivered the relay 114 energizes to disengage the springs 116 and 117, whereby the protecting potential is removed from the connector bank contacts of the calling line, and thus when a subscriber calls his own line the connector switch will not receive the busy-release.

The first-selector switch D is a modified form of the selector switch disclosed in United States Patent No. 815,321, granted

March 13, 1906, to Keith, Erickson & Erickson, with the exception that there are no normal conductors such as those of the said patent. There is also no use in the selector switch D for a bridge-cut-off relay, and it is also omitted, and the line relays are connected directly to the battery lead. The private normal conductor, such as the private normal conductor of the said selector patent, is of no necessity in connection with the selector switch D, and is also omitted. Since like parts are likewise represented throughout the drawings, the vertical magnet 96 and the rotary magnet 97, the release magnet 98, and the private magnet 99 will be recognized and understood. The said private magnet 99, of course, controls the side switch wipers 100, 101, 102 and 103, the said private magnet also controlling the circuit of the vertical magnet 96, in the usual manner, by means of the springs 105 and 106. The vertical movement of the switch shaft, and, therefore, of the wipers 119, 120 and 121, is controlled by the vertical magnet, and the rotary movement by the rotary magnet 97, the rotary magnet circuit being provided with the usual interrupter springs 107. The operative magnets of the switch, of course, are controlled by the subscriber through the medium of the vertical and rotary line relays 108 and 109, as is well known. Said relays have under their control the usual springs 110, 111 and 112. By means of the back-release relay 115 the release of the switch D is brought about after the side switch has passed to third position.

The connector switch E may also be of any suitable or approved type, for instance of the general type described in the United States Patent No. 815,176, granted March 13, 1906, to Keith, Erickson & Erickson, provided with certain improvements. The mechanical details of the first-selector and connector, as is well known, are very much the same, although there is some material difference in the circuits. The connector switch shaft (not shown), like the first-selector switch shaft, carries the line wipers 125 and 126 and the private wiper 127. The connector switch is also controlled by the calling subscriber through the medium of the vertical and rotary line relays 128 and 129. The vertical line relay 128 directly controls the vertical magnet 130, and also the rotary magnet 131 and the ringer relay 132. The purpose of the vertical magnet 130 is to give the shaft and shaft wipers a vertical motion, and the rotary magnet 131 imparts to the shaft and shaft wipers a rotary or circular motion. The rotary line relay controls the private magnet 133 which, under certain conditions, in turn controls the vertical and rotary magnets 130 and 131, release magnet 134, and also the side switch

wipers 135, 136, 137 and 138. The side switch of the connector, like the side switch of the first-selector, has a normal or first position, a second position and third position. The release magnet 134 is also controlled by the line relays 128 and 129, conjointly. By the condensers 140 and 141 the circuit through the connector is divided into two sections. The central office is equipped 10 with busy-signaling apparatus of any suitable design, comprising an interrupter in series with the primary winding of the induction-coil (for example, shown at K), whereby a busy-signaling current is induced 15 in the secondary winding of the said coil.

A clearer understanding of my improved system may be obtained by considering its operation when one subscriber calls another. Assume, for example, that the subscriber at 20 substation A desires to call the subscriber at substation A' to which is allotted the number 220. When the receiver 2 is removed from the switch-hook 3 the switch-hook ascends, carrying the rod 43 out of engagement 25 with the locking relay 17. To call the number 220 the subscriber at substation A operates the calling device once, in the well-known manner, for each digit. The preliminary impulse for operating the line 30 switch C occurs when the calling subscriber rotates the dial forward for the first digit, whereby the rotary impulse spring 24 is pressed against the ground post 20. As a result, the trip magnet 47 of the line switch 35 C is energized by a flow of current from ground G' to the springs 46 and 41 of the locking relay, to the springs 18 and 19, ground post 20, impulse spring 24 to the rotary line conductor 32, conductor 153 (Fig. 2), cut-off relay springs 154 and 155 to the trip magnet 47, thence through said trip magnet to the conductor 156, springs 157 and 88 of the relay 73, springs 55 and 86 of the motor magnet 71, through the 40 winding of the motor magnet 71 to the battery lead 160, thence through battery B to ground G. Although this circuit includes the motor magnet 71, the said magnet does not operatively energize, and the trip magnet 47 alone operates. As soon as the trip magnet 47 energizes, the armature 51 is attracted, and the plunger 44 is liberated and thrust into the bank terminal Q by the spring 58. When the plunger 44 engages the bank terminal Q an energizing circuit is closed 45 through the motor magnet relay 73, which in turn operates to close a circuit through the motor magnet 71. The motor magnet then operates to place the idle plungers 50 which are in locking engagement with the shaft 60 opposite the next idle bank terminal similar to the terminal Q. The circuit through the relay 73 extends from ground G' through the winding 161 of the relay 73 55 to the segment 74, wiper arm 75, segment 60

84, conductor 162, bank terminal springs 68 and 67, release magnet 48 to the battery lead 160, thence through battery B to ground G. Although this circuit includes the release magnet 48, the said magnet does not operatively energize, since the windings of the relay 73 are wound to a high resistance, while the winding of the release magnet is comparatively low. The relay 73, upon energizing, operates to place the springs 87 and 88 in contact, whereby a circuit is completed through the motor magnet 71, extending from ground G' through the springs 87 and 88, motor magnet springs 85 and 86, through the winding of the motor magnet 71 to the battery lead 160, thence through battery B to ground G. The motor magnet 71, upon energizing, attracts its armature 81, whereby the pawl 82 engages the ratchet wheel 72 and rotates the said wheel one step. When the armature 81 is attracted against the magnet cores the springs 85 and 86 disengage, thereby breaking the energizing circuit through the motor magnet. The cam-arm 76, being in engagement with the pin 77, is operated to advance the plunger shaft 60 (and consequently all idle plungers that may be in normal position) one step to another trunk terminal similar to the terminal Q. Also, the wiper 75 is carried from the contact point 84, which corresponds to the terminal Q, to the contact point 89, which latter corresponds to the terminal before which the advanced idle plungers are now resting. At the instant that the said plunger 44 enters the said bank terminal Q, the following springs are pressed into contact: 63 and 64, 65 and 66, 67 and 68, and 69 and 70. The engagement of the springs 69 and 70 establishes a circuit from ground G', 105 by way of the normal conductor 95, to the connector private bank contacts corresponding to the line that terminates in the line switch C, whereby a guarding potential is set up to prevent any subscriber from calling the said line after the calling subscriber at substation A operates his dial preparatory to making a call, as explained. The circuit over which the said guarding potential is established extends from ground G', 110 springs 116 and 117, through the bank springs 70 and 69 to the private normal conductor 95, thence to the connector private banks. The engagement of the springs 69 and 70 also closes a circuit through the cut-off relay 46, extending from ground G', 115 springs 116 and 117, through the bank springs 70 and 69, conductor 163, relay 46 to the battery lead 160, thence through battery B to ground G. The said relay, upon energizing, breaks the contact between the spring 155 and 154. When the said springs disengage, the rotary line conductor 32 is disconnected from the trip magnet 47. 120

The closure of connection between the 130

springs 67 and 68 establishes a guarding potential at the master switch bank contact 84, over the following circuit: from battery B to the battery lead 160, thence through the release magnet 48 and springs 67 and 68 over the conductor 162 to the said contact point 84. It will be understood that the bank terminal Q, being the first bank terminal of the line switch bank, corresponds to the first segment 84 of the master switch bank O. This guarding potential protects the seized trunk conductors 90, 91 and 92 from being seized by other plungers. Suppose that the master switch has operated and carried the wiper 75 to the last contact point 164. Now, when the motor magnet 71 operates for the next step, the wiper 75 engages the contact point 84 upon which there is a guarding potential. An energizing circuit is established through the differential relay 73 which in turn operates to close an energizing circuit through the motor magnet 71. The current through the said relay 73 flows from the said contact 84 through the wiper 75 to the common segment 74, and through the winding 161 of the differential relay 73 to ground G. When the differential relay 73 attracts its armature the differential relay springs 87 and 88 are pressed into contact, thereby closing an energizing circuit for the motor magnet 71 from ground G through the said springs 87 and 88, through the motor magnet springs 85 and 86, motor magnet 71, thence to the battery lead 160, and through battery B to ground G. The motor magnet then operates, as previously explained, to rotate the ratchet wheel 72 one step for advancing the plunger shaft 60 one step, and the master switch bank wiper 75 is also advanced one step and brought into engagement with the second segment 89. The plunger shaft 60, when thus advanced one step, carries all idle plungers that are in locking engagement with the said shaft opposite the next bank terminal, as previously explained. If there should be a guarding potential at the bank segment 89 of the master switch bank the differential relay 73 will remain energized, whereby the energizing circuit through the motor magnet 71 is again completed, when the motor magnet springs 85 and 86 again engage; and as a result the motor magnet 71 is again operated, whereby the plunger shaft 60 and the master switch bank wiper 75 are advanced another step. This process continues as long as the wiper 75 continues to find segments with guarding potentials. As soon as an idle segment is found, however, the energizing circuit through the differential relay 73 is broken, at which time the said relay in turn breaks the energizing circuit for the motor magnet 71 until the next subscriber makes a call. The closure of connection between the springs 63 and 64 extends the calling sub-

scriber's vertical line conductor 31 to the vertical trunk conductor 90 and to the side switch wiper 100 of the first-selector D (Fig. 1). The closure of contact between the springs 65 and 66 in a similar manner extends the subscriber's rotary line conductor 32 to the rotary trunk conductor 91 and to the side switch wiper 101 of the selector D. The subscriber has thus established connection with the selector D and is ready to begin operating his calling device for the first digit. The first digit being 2 the subscriber operates his dial accordingly, grounding the vertical line conductor 31 each time that the spring 23 is pressed onto the ground post 20. As a result the vertical line relay 108 of the first-selector D is energized by a flow of current from the substation ground G' through the locking relay springs 40 and 41, co-operating ground springs 18 and 19 to the ground post 20, thence through the spring 23 to the vertical line conductor 31, line switch bank springs 63 and 64, vertical trunk conductor 90, side switch wiper 100 of the selector D, contact point 170, vertical line relay 108 to the battery lead 160, thence through battery B to ground G. The relay 113, being connected to the trunk conductor 90, energizes in multiple with the vertical line relay 108, but its operation at this time is without effect. Each time that the vertical line relay 108 energizes, the line relay spring 111 is pressed onto the ground spring 110. The vertical magnet 96 is thereby energized, and the wipers 119, 120 and 121 of the selector D are raised to the second bank level and thus brought opposite the first contact of said level. The energizing circuit for the said vertical magnet 96 extends from ground G through the springs 110 and 111, private springs 105 and 106 to the vertical magnet 96, thence to the battery lead 160, and through battery B to ground G. The spring 24 is then pressed onto the ground post 20, grounding the rotary line conductor 32 and energizing, therefore, the rotary line relay 109 of the selector D. The energizing current passes from ground G' to the rotary line conductor 32, thence it flows through the line switch bank springs 65 and 66, rotary trunk conductor 91, side switch wiper 101 of the selector D, contact point 171, rotary line relay 109, to the battery lead 160, and through battery B to ground G. The relay 114, being connected to the trunk conductor 91, energizes in multiple with the rotary line relay 109. The rotary line relay, upon operating, presses the line relay spring 112 onto the ground spring 110, thereby establishing a circuit through the private magnet 99 from ground G through the springs 110 and 112 to the private magnet 99, and through the said magnet to battery lead 160, thence through battery B to ground G. The pri-

vate magnet, upon energizing and deenergizing, permits the selector side switch to pass from first to second position, permitting the side switch wipers 102 and 103 to engage the contact points 172 and 173, respectively. The closure of connection between the side switch wiper 103 and the contact point 173 sets up an energizing circuit for the rotary magnet 97 from ground ⁷⁰ to the contact point 173, through the side switch wiper 103, interrupter springs 107, rotary magnet 97 to the battery lead 160, and then through battery B to ground G. The said rotary magnet 97 then operates to rotate the wipers 119, 120 and 121 of the selector D into engagement with a trunk line leading to some idle connector switch, and in the particular case under consideration to the connector switch E. If the wipers have to pass over busy trunk lines, then as soon as the private wiper 121 engages a grounded contact point the private magnet 99 energizes again, locking the side switch in second position. The energizing circuit for said private magnet extends from the grounded terminal G of battery B through an occupying switch (not shown) to the private wiper 121, thence over the conductor 174, through the back-release ⁸⁵ relay 115 to the side switch wiper 102, contact point 172, private magnet 99, thence through said magnet to the battery lead 160, and through battery B to ground G. The private magnet 99, upon thus becoming energized, locks the grounded side switch wiper 103 in engagement with the contact point 173, whereby the rotary magnet 97 will be energized intermittently until the wipers are carried beyond the last busy ⁹⁰ line. At the instant that the private wiper leaves the last busy contact point the energizing circuit through the private magnet 99 is destroyed, and as a result the selector side switch passes to third position. If, however, there are no busy trunk lines, the rotary magnet 97 releases the side switch to third position as soon as the wipers are carried into engagement with the first trunk line. As soon as the side switch passes to ¹⁰⁰ third position, as stated, the subscriber's line conductors 31 and 32 are extended to the conductors 175 and 176, which, in this case, it is assumed lead to the connector switch E. The extension of the line occurs, of course, as soon as the side switch wipers 100 and 101 engage the contact points 177 and 178, respectively. Not only is the subscriber's line thus extended, but a guarding potential is established at the private wiper ¹¹⁵ 121, when the side switch wiper 102 passes onto the ground contact point 179, for protecting the seized trunk line from interference by other calling subscribers. This guarding potential is established from ground G^o to the contact point 197, thence through the side switch wiper 102, back-release relay 115, and conductor 174 to the private wiper 121. It will be necessary, of course, that the energizing circuit for the rotary magnet 97, to which reference has ¹²⁰ already been made, be destroyed when the idle trunk line is seized. This occurs when the side switch wiper 103 leaves the contact point 173. The second digit of the desired number being 2 the subscriber operates his dial to ground the vertical line conductor 31 twice and the rotary line conductor 32 once. As a result the vertical line relay 128 of the connector E is energized twice and the rotary line relay 129 once. For the second digit 2 the vertical impulse spring 23 is pressed onto the ground post 20 twice, whereby an energizing circuit is closed through the vertical line relay 128. This circuit extends from ground G' through the ground post 20, spring 23, line conductor 31, springs 63 and 64, trunk conductors 90 and 175, vertical line relay 128 to the battery lead 160, thence through battery B to ground G. Each time the vertical line relay 128 is energized, the line relay springs 197 and 198 are pressed into contact, thereby closing an energizing circuit through the vertical magnet 130 which operates in the usual manner, one step at a time. The shaft wipers 125, 126 and 127 are, therefore, raised two steps and brought opposite the level in which are located the normal terminals of the line of substation #220. The rotary impulse spring 24 makes contact with the ground post 20, thereby closing an energizing circuit through the rotary line relay 129 extending from ground G' through the ground post 20 and spring 24, line conductor 32, trunk conductors 91 and 176, ringer springs 200 and 199, through the rotary line relay 129 to the battery lead 160, thence through battery B to ground G. The rotary line relay, upon operation, closes an energizing circuit through the private magnet 133 which operates to release the connector side switch from first to second position. The last digit being naught the calling device is operated as previously described, grounding the vertical line conductor 31 ten times and the rotary line conductor 32 once. The vertical and rotary line relays 128 and 129 are operated over previously traced circuits. However, when the line relay springs 197 and 198 engage, a circuit is then closed through the rotary magnet 131 instead of through the vertical magnet 130. Each time that the rotary magnet is energized it operates to rotate the shaft and shaft wipers 125, 126 and 127 one step at a time until the said wipers are carried into engagement with the normal conductors 93, 94 and 95, the former two of which lead to the line terminals of the calling subscriber. The energizing of the rotary line ¹³⁰

relay 129, as previously stated, completes an energizing circuit through the private magnet 133 which now operates to release the side switch from second to third position, thus placing the side switch wipers 135, 136, 137 and 138 in contact with their respective contact points 195, 196, 204 and 201. It will be understood, of course, that the busy-release does not occur when a subscriber calls back on his own line, as will be explained. The busy-release follows only when a subscriber calls onto a line other than his own which is busy. The release of the side switch occurs when the private magnet 133 energizes, as heretofore explained. At the instant that the said side switch passes to third position, the connector side switch wipers 135 and 136, having engaged the contact points 195 and 196, extend the calling subscriber's line conductors into connection with the normal conductors 93 and 94. Since the said normal conductors 93 and 94 lead back to the calling line, it will be evident that the calling subscriber has operated to connect the connector E with his own line. It will be remembered that when the line switch C first operated to close the bank springs 69 and 70 into contact, the guarding potential was established over the private normal conductor 95 to the connector private bank contacts corresponding to the line allotted to the line switch C. One of the said contacts is now engaged by the connector private wiper 127. Had the said guarding potential remained constantly on the said contact point, it would have been impossible for the connector side switch to have passed to third position, as described. Instead, however, the said connector switch would have been released. It will be seen that the energizing circuit for the connector rotary line relay 129 comprises the rotary private normal relay 114 in multiple, and, therefore, that the said relay energizes in unison with the connector rotary line relay 129. That being the case, and since the guarding potential at the connector private bank contacts from the line switch ground G* flows through the springs 116 and 117 of the said private normal relay 114, the guarding potential is interrupted at the same time that the connector rotary line relay 129 operates the private magnet 133. It is evident, therefore, that at the instant that the connector side switch passes to third position there is no guarding potential at the connector private bank contacts to interfere with the establishment of the desired connection.

60 The calling subscriber having completed the call then proceeds to signal the called substation #220. In order to signal the called subscriber the calling subscriber presses the signaling button 37, carrying the spring 35 into engagement with the grounded contact point 38. As a result the vertical line conductor 31 receives a current impulse from the substation ground G' to the lock-out relay springs 40 and 41, ground springs 18 and 19 to the contact point 38, 70 spring 35, thence through the springs 34 and 33 to the vertical line conductor 31. Grounding said conductor operates the connector vertical line relay 128 over circuits that have been pointed out. The operation of the said relay 128 causes the energization of the connector ringer relay 132 over the following circuit: From ground G' at the connector through the line relay springs 197 and 198, private springs 158 and 159, side switch 80 wiper 138, contact point 201, to the ringer relay 132, thence to the battery lead 160, and through battery B to ground G. The energization of said ringer relay 132 bridges the ringer generator R across the normal conductors 93 and 94, whereby ringing current is projected over the line conductors 31 and 32 to the substation #220 for operating the ringer 202 at the said substation. It should be explained that the connector E, like all 90 the connectors of the two-hundred group, may be arranged to draw its ringing current from a ringer generator R that furnishes current of such character that only the ringer 202 of the substation #220 will be 95 operated by said current, while the ringers of all other substations on the same line may be so tuned that they will not respond to the current from said generator. Similarly, the connectors of the three-hundred group, 100 which are employed when substations of this group are called, may be arranged to draw their ringing current from a ringer generator that furnishes current of such character that only ringers tuned to respond to 105 the current of this particular character will be operated. Likewise, the connectors of the four and one hundred groups may in turn draw their ringing current from still other generators that supply current of such character that only those ringers that are correspondingly tuned will operate. It is evident, then, that when generator current is projected out on the line by the connector E of the two-hundred group only the ringer 115 202 will be operatively affected. The path of the ringing current is as follows: From the ringer generator R and through the ringer relay springs 203 and 204, through the side switch wiper 135 to the vertical 120 normal conductor 93, thence to the vertical line conductor 31, cam-arm 205 of the switch-hook, spring 206 (since the said cam and spring engage when the switch-hook is in normal position), through the ringer 202 125 at substation #220, condenser 207, back to the rotary line conductor 32, thence over the rotary normal conductor 94, wiper 136, ringer relay springs 208 and 209 to the ringer generator R. The subscriber at sub- 130

station #220, upon responding, bridges his receiver 210 in series with the condenser 207, and secondary winding 211 of the induction-coil 212, in multiple with the receiver 2, which is in series with the condenser 12 and secondary winding 22 of the substation #420, across the line conductors 31 and 32. When the called subscriber removes his receiver 210, as shown in Fig. 1, the switch-hook upon rising permits the springs 214, 215 and 216 and the springs 217 and 218 to engage before the springs 221^a and 220 disengage, in which case the substation lock-out relay 221 energizes over the following circuit: from the substation ground G¹, through the springs 222 and 223, spring 224, springs 229 and 221^a to the relay 221, thence through the springs 215 and 214 to the vertical conductor 31, and vertical private normal relay 113 and vertical line relay 128 of the connector E in multiple to the battery lead 160, thence through battery B to ground G. The substation relay 221, upon energizing, attracts and locks its armature, as described in connection with the lock-out relay 17^a of substation #420. When the substation relay 221 energizes, the springs 222 and 223 separate, destroying the connection between the substation ground G¹ and the ground spring 224, so that the said subscriber is deprived of the means for grounding either of the line conductors 31 or 32.

If, while the subscribers at substation #220 and #420 are conversing, the subscriber at substation #320 removes his receiver from the switch-hook, the substation relay 225 is energized over similar circuits, and locks in the same manner as the relay 221 of the substation #220. The effect of locking the said relay 225 produces the same results in connection with substation #320 that locking the relay 221 produces with respect to substation #220. The subscriber at substation #320 is, therefore, made powerless to interfere with the established connection, since his ground is cut off, as explained in connection with substation #220. Of course, when the subscriber at the substation #320 hangs up his receiver the link 226 is carried down by the switch-hook, whereby the relay 225 is unlocked, as explained. The same is true with respect to the substation #220 and the relay 221.

After the subscribers are through talking, if the subscriber at substation #420 hangs up his receiver he grounds the vertical and rotary line conductors 31 and 32 simultaneously, thereby producing a release of the switches through the medium of which the connection has been established. As the switch-hook 3 descends, the release springs 7, 8 and 9 are pressed into contact, whereby the vertical and rotary line conductors are grounded. Under these conditions the line relays 128 and 129 are energized, whereby the trunk-release springs 227 and 228 are pressed into contact, with the result that an energizing circuit is established through the release magnet 134 of the connector E in series with the back-release relay 115 of the selector D. The release magnet 134 of the connector, upon energizing, restores the said switch and the switch shaft to normal position, in the well known manner, at which time the line and private wipers 125, 126 and 127 are, of course, disconnected from the normal conductors 93, 94, and 95. The energizing of the back-release relay 115 carries the back-release relay springs 229 and 230 into engagement, as a result energizing the release magnet 98 from ground G¹ through the said springs 229 and 230, and the release magnet 98 to battery B. The selector release magnet 98, upon energizing, attracts its armature and puts the same in readiness to release the switch when the release springs at the substation disengage, as is well known. The back-release relay 115 not only energizes the magnet 98, but also the release magnet 48 of the line switch C, since the said release magnet 48 is connected in multiple with the release magnet 98 of the selector D. The current through the said release magnet 48 flows from ground G¹ through the back-release relay springs 229 and 230 to the third trunk conductor 92, thence through the line switch bank springs 68 and 67, through said magnet 48 to the battery lead 160, and through battery B to ground G. When the release magnet 134 (Fig. 3) energizes, the armature 51 is attracted, whereby the armature 51 of the trip magnet 47 is raised and the catch terminal 53 latches the terminal 57 of the plunger arm 43, remaining thus in readiness to restore the individual switch when the release magnet 134 deenergizes sufficiently. As soon as the substation release springs 7, 8 and 9 separate, the energizing circuits of the rotary and vertical line relays 129 and 128 of the connector E are destroyed. As a result, the energizing circuit through the release magnet 134 and the back-release relay 115 is broken, restoring the connector switch to normal condition. The deenergization of the back-release relay 115 in turn causes the deenergization of the selector release magnet, with the result already stated, and also causes the deenergization of the release magnet 48 of the line switch C. When the release magnet 48 of the said line switch deenergizes, the plunger 44, through the medium of the armatures 51 and 49, is withdrawn and lifted into engagement with the plunger shaft 60, destroying, of course, the energizing circuit of the cut-off relay 46, removing the guarding potential from the master switch bank O and from the connector banks, and disconnecting the sub-

scriber's line from the first-selector. It will be clear, of course, that the private normal relays 113 and 114 will also be restored as soon as the line switch C is restored.

Upon a careful inspection it will become evident that the operations herein described are sufficient to enable those skilled in the art to understand how a connection can be established with a line other than that of the calling subscriber, in which case the connector wipers 125, 126 and 127 will establish connection with normal conductors other than the normal conductors 93, 94 and 95, which normal conductors will, of course, be allotted to the other line. In that case—that is, when the subscriber at substation #420 is connected with a subscriber of some other line—then if the subscriber #320 attempts to come in on the line the energizing circuit for the substation lock-out relay 225 comprises the vertical private normal relay 113 and the connector vertical line relay 128, as explained. It will be evident, furthermore, that the private normal relays 113 and 114 will play no part in connection with the calling connector, and that if the subscriber #420 calls the other line while said line is busy, the private wiper 127 will then find a guarding potential established at the connector private bank contact allotted to the desired line. In that case, as is well known, the connector side switch does not pass to third position, but is released, and the calling subscriber receives a busy-signal.

The busy-release occurs when the rotary line conductor 32 is grounded for the last time, and at the instant that the private magnet 133 is energized, at which time the private springs 231 and 232 are carried into engagement and an energizing circuit is established through the release magnet 134 as follows: The current flows from the private bank contact to the private wiper 137, side switch wiper 137, private springs 232 and 231, release magnet 134, thence through battery B to ground G. This last rotary impulse comes in while the side switch is in second position. After the connector is released, then if the calling subscriber presses his signaling button 37 he grounds the vertical line conductor and energizes the vertical line relay 128 of the connector, and also raises the connector switch shaft, which latter, upon rising, closes the off-normal springs 233 and 234, thereby establishing a busy-signal through the calling substation. The busy-signaling current flows from the secondary winding of the busy coil 104 through the off-normal springs 234 and 233 to the side switch wiper 136, thence through the condenser 141 to the calling substation, and back over the vertical side of the line through the vertical line relay 128 and private normal relay 113 to the battery lead 160, and back to the coil 104. When the

calling subscriber hears the busy-signal he hangs up his receiver and grounds both of the line conductors 31 and 32 simultaneously, thereby energizing the vertical and rotary line relays 128 and 129, with the result already explained—that is, with the result that all of the switches are released and restored to normal condition. Suppose that the substation #420 is called by another substation, #500 for example. Assume that the line switch allotted to the line #500 seizes the trunk line leading to the first-selector D, and assume, also, that the connector E is of the four hundred group and is the one selected by the first-selector D. The established connection would then be the same as that shown in Fig. 1, except that the trunk line leading to the connector E would be connected with the line switch allotted to the line #500 instead of with the line switch C, as shown. In that case, if a subscriber located on the same line as the subscriber #220 is located were to remove his receiver and attempt to make a call while the line is busy, the operation of the dial and grounding of the line is without effect, since the condensers 140 and 141 separate the calling and called lines. When one subscriber has called another line, the release is the same as the release already described, and connection with the called line is severed as soon as the connector wipers are disengaged from the banks.

From the foregoing it will be seen that the subscriber can release without liability of energizing the trip magnet 47, as the energizing of the relay 114, and the consequent deenergizing of the cut-off relay 46, is off-set or neutralized by the energizing of the relay 113, which latter closes a substitute circuit through the relay 46 to prevent energizing of the said trip magnet. In this way the connector can release, and the relay 114 can energize, and still the cut-off relay 46 will not deenergize, because there is still a local ground circuit through the winding of the cut-off relay. With this arrangement the switches will release with certainty, and all possibility of leaving the individual trunking switch off-normal is precluded or greatly reduced. It will be seen, of course, that the relay 113 does not interfere with the momentary interruption of the guarding potential by the relay 114, when a subscriber on a party-line calls back on the same line for the purpose of communicating with another subscriber thereon.

It will be obvious that in this system the resistance of the magnets may be varied to any extent consistent with the successful operation of the same. Not only may the resistances of the line relays (for example the line relays 128 and 129 of the connector E) be varied, but the resistance of the operating magnets (for example the release

magnets 48, 98 and 134) may likewise be varied. It will also be obvious that the springs used as contacts may be adjusted in any manner desired and their tensions varied to any extent in order to control the speed and operation of the armatures associated with them. For example, the springs of the motor magnet relay 73 may be stiffened or weakened, as may be found convenient or desirable. In regard to this motor magnet relay it should be stated, and it is perfectly obvious, that although it is shown as a double-wound differential coil the upper winding is not absolutely necessary, since the system will operate without it.

What I claim as my invention is:—

1. In a telephone system, a connector, a line, a plurality of subscribers' substations thereon, a trunking switch, a cut-off relay therefor, means for establishing a guarding potential when the line is in use, means for momentarily removing said guarding potential when one of the subscribers calls back on the same line, a circuit for energizing said relay during conversation, means for releasing the connector, and another circuit for energizing said relay after said first-mentioned circuit is opened to prevent operation of said trunking switch during the release.

2. In a telephone system, a connector, a line, a plurality of subscribers' substations thereon, a relay individual to said line, means for establishing a guarding potential when the line is busy, automatic means for momentarily removing said guarding potential when one of the subscribers calls back on the same line, means for keeping said relay energized during conversation, means for releasing the connector, and automatic means for closing a local circuit through said relay when a subscriber hangs up his receiver to prevent deenergization of said relay during the release.

3. In a telephone system, a line, trunk lines, an individual trunking switch for said line, and a pair of relays bridged across each trunk line, said trunking switch provided with a cut-off relay, and energizing circuits for said cut-off relay, the relays of the trunk lines being provided with means whereby the energizing of any pair of relays serves to open one circuit and close another through the said cut-off relay.

4. In a telephone system, a line, a relay individual thereto, a calling mechanism, switches controlled thereby, means for keeping said relay energized during use of the line for conversational purposes, a plurality of energizing circuits for said relay, and means for opening one circuit and closing another when a subscriber on said line hangs up his receiver.

5. In a telephone system, a line, a relay individual thereto, means for energizing

said relay during use of the line for conversational purposes, a trunk line, a pair of relays bridged across said trunk line, and means whereby the energizing of said pair of relays opens one circuit and closes another through said first-mentioned relay.

6. In a telephone system, a line, a plurality of subscribers' substations thereon, automatic means for establishing a guarding potential when the line is busy, automatic means for momentarily removing said guarding potential when one of the subscribers calls back on the same line, a relay individual to the line, means for energizing the relay, and automatic means for preventing the deenergizing of said relay during the release.

7. In a telephone system, a line, a trunk-selecting switch connected thereto, a cut-off relay in said switch, two circuits therefor, a talking circuit controlled by said relay, a pair of relays connected in multiple, and means whereby the energizing of said pair of relays opens one circuit and closes another through the said cut-off relay.

8. In a telephone system, a line, a controlling magnet normally connected therewith, a cut-off relay for disconnecting said controlling magnet from the line, two circuits for said cut-off relay, a talking circuit controlled by said cut-off relay, a pair of relays connected in multiple, and means whereby the energizing of said pair of relays opens one circuit and closes another through the said cut-off relay.

9. In a telephone system, a line, a trunking switch for said line, a cut-off relay therefor, two circuits for said relay, a talking circuit controlled by said relay, a pair of relays, and means whereby the energizing of said pair of relays opens one circuit and closes another through the said cut-off relay.

10. In a telephone system, a line, a controlling magnet normally connected therewith, a cut-off relay for disconnecting said controlling magnet from the line, two circuits for said cut-off relay, a talking circuit controlled by said cut-off relay, a pair of relays, and means whereby the energizing of said pair of relays opens one circuit and closes another through the said cut-off relay.

11. In a telephone system in which the subscribers' lines are divided into groups, means having one motion to select groups, and another motion to connect with a line in the selected group, a line, a plurality of subscribers' substations thereon, a trunking switch, a cut-off relay therefor, means for establishing a guarding potential when the line is in use, means for momentarily removing said guarding potential when one of the subscribers calls back on the same line, a circuit for energizing said relay during conversation, and another circuit for energizing

said relay after said first-mentioned circuit is opened to prevent operation of said trunking switch during the release between calling and called subscribers.

5 12. In a telephone system in which the subscribers' lines are divided into groups, means having one motion to select groups and another motion to connect with a line in the selected group, a line, a plurality of 10 subscribers' substations thereon, a relay individual to said line, means for establishing a guarding potential when the line is busy, automatic means for momentarily removing said guarding potential when one of the 15 subscribers calls back on the same line, means for keeping said relay energized during conversation, and automatic means for closing a local circuit through said relay when a subscriber hangs up his receiver to 20 prevent deenergization of said relay during the release between calling and called subscribers.

13. In a telephone system in which the subscribers' lines are divided into groups, 25 means having one motion to select groups and another motion to connect with a line in the selected group, a line, trunk lines, an individual trunking switch for said line, and a pair of relays bridged across each 30 trunk line, said trunking switch provided with a cut-off relay, and energizing circuits for said cut-off relay, the relays of the trunk lines being provided with means whereby the energizing of any pair of relays serves 35 to open one circuit and close another through the said cut-off relay.

14. In a telephone system in which the subscribers' lines are divided into groups, means having one motion to select groups 40 and another motion to connect with a line in the selected group, a line, a relay individual thereto, means for keeping said relay energized during use of the line for conversational purposes, a plurality of energizing 45 circuits for said relay, and means for opening one circuit and closing another when a subscriber on said line hangs up his receiver.

15. In a telephone system in which the 50 subscribers' lines are divided into groups, means having one motion to select groups and another motion to connect with a line in the selected group, a line, a relay individual thereto, means for energizing said 55 relay during use of the line for conversational purposes, a trunk line, a pair of relays bridged across said trunk line, and means whereby the energizing of said pair of relays opens one circuit and closes another through said first-mentioned relay.

16. In a telephone system in which the subscribers' lines are divided into groups, means having one motion to select groups

and another motion to connect with a line in the selected group, a line, a plurality of 65 subscribers' substations thereon, automatic means for establishing a guarding potential when the line is busy, automatic means for momentarily removing said guarding potential when one of the subscribers calls back 70 on the same line, a relay individual to the line, means for energizing the relay, and automatic means for preventing the deenergizing of said relay during the release.

17. In a telephone system in which the 75 subscribers' lines are divided into groups, means having one motion to select groups and another motion to connect with a line in the selected group, a line, a trunk-selecting switch individual to said line, a cut-off 80 relay for said switch, two circuits for said relay, a talking circuit controlled by said relay, a pair of relays connected in multiple, and means whereby the energizing of said pair of relays opens one circuit and 85 closes another through the said cut-off relay.

18. In a telephone system in which the subscribers' lines are divided into groups, means having one motion to select groups and another motion to connect with a line 90 in the selected group, a line, a controlling magnet normally connected therewith, a cut-off relay for disconnecting said controlling magnet from the line, two circuits for said cut-off relay, a talking circuit controlled by 95 said cut-off relay, a pair of relays connected in multiple, and means whereby the energizing of said pair of relays opens one circuit and closes another through the said cut-off relay.

19. In a telephone system in which the subscribers' lines are divided into groups, means having one motion to select groups and another motion to connect with a line in the selected group, a line, a controlling 105 magnet normally connected therewith, a cut-off relay for disconnecting said controlling magnet from the line, two circuits for said cut-off relay, a talking circuit controlled by said cut-off relay, a pair of relays, and 110 means whereby the energizing of said pair of relays opens one circuit and closes another through the said cut-off relay.

20. In a telephone system, a subscriber's individual line switch adapted to perform 115 a preliminary non-numerical trunking operation, a private normal conductor, and means normally disconnected from said switch for maintaining a ground on said conductor until the switch is released.

Signed by me at Chicago, Cook county, Illinois, this 26 day of June, 1907.

EDWARD A. MELLINGER.
